UNITED STATES PATENT OFFICE.

JOHN DAVIDSON, OF MANCHESTER, ENGLAND.

INTERNAL-COMBUSTION ENGINE.

1,317,355.

Specification of Letters Patent. Patented Sept. 30, 1919.

Application filed July 7, 1919. Serial No. 303,145.

To all whom it may concern:

Be it known that I, JOHN DAVIDSON, a subject of the King of Great Britain, residing at Manchester, in the county of Lancashire, England, have invented certain useful Improvements in and Connected with Internal-Combustion Engines, of which the following is a specification.

This invention relates to improvements in and connected with the two cycle type of internal combustion engines, such as described in my British application for Letters Patent No. 119,401, dated March 19th 1918, in which the charging piston works in tandem fashion with and forms a tubular extension of the working piston and passage between the charging cylinder and the working cylinder and having ports serving also as a valve controlling the distribution of the mixture to the charging and working cylinders.

The object of this invention is the provision of means whereby the said type of engine is rendered applicable for large power and simplicity and compactness of construction and efficiency in action are combined.

I attain these objects by the means illustrated in the accompanying drawings which illustrate a single acting integral combustion engine constructed in accordance with this invention,

Figure 1 being a longitudinal vertical section and Fig. 2 an end view thereof.

Referring to the drawings, which illustrate a single acting engine constructed in accordance with this invention, *a* and *b* are respectively the working cylinders and pistons, and *c* and *d*, the charging or pump cylinders and pistons arranged tandem. *e* are the tubular extensions of the working pistons *b* at the top provided with the charging or pump piston *d*. *a'* are the exhaust ports in the end of the working cylinders.

In connection with each of the said charging or pump cylinders *c*, a piston valve *f* is employed actuated from the crank shaft *g* of the engine by an eccentric *h* and adapted to control the inlet to and delivery of air from the top side of charging piston *d* and to control the inlet to and delivery of gas or mixture from the bottom side of the charging or pump piston *d*.

To obtain a definite pure air scavenge, the pure air and mixture are supplied by separate main pipes *i*, *k*, the pure air pipe *i*

being connected with the top ends and pipe *k* with the bottom ends of the piston valves *f*, the pure air being admitted to the top of said valves.

The charging or pump pistons *d* simply act as compressors, the air being compressed on the top side and delivered into the main pure air pipe *i* and the mixture being compressed on the underside and delivered into the mixture main *k*.

The tubular extension *e*, moves in barrels *m* arranged concentrically between the working and charging or pump cylinders *a* and *c* respectively and having ports *n* connected with said main mixture supply pipe *k*, through which the mixture is admitted, each time the ports *o* in the tubular extensions *e* meet the ports *n*.

The top of each charging or pump cylinder *c* has a centrally extending casing *p* in which moves the open upper end of a tube *q* the lower end of which is secured into the tubular extension *e* and has radial ports *r* adapted to register with inlet ports *s* in the end of the working cylinder *a*.

The said casings *p* by means of elbow pipes *t*, are connected with the main pure air supply pipe *i* to permit of pure air passing down the tubes *q* and through the ports *r* and *s*, enter the working cylinder *a* and thus thoroughly scavenge the same immediately the exhaust ports *a'* of the engines have been opened.

The engine described operates as follows:—

As already explained the charging pump *c*, *d* has a dual function. The top side of piston *d* is used to compress air to a few pounds per square inch which is delivered into main *i* and the bottom side of the piston *d* is used to compress the mixture which is delivered into main *k*. It will thus be seen that pipe *i* is always charged with air at a small pressure and pipe *k* with mixture at a small pressure.

As the working piston *b* moves downward, it first uncovers the exhaust ports *a'* and allows the burnt gases to escape, as the piston moves farther down the small ports *r* overrun ports *s* and allow pure air to enter the working cylinder to scavenge out the burnt gases, and immediately this has taken place the mixture flows in and charges the working cylinder. On the return stroke, the air mixture, and exhaust ports are cut off and the

mixture compressed and when the piston is nearing the top of its stroke, the mixture is fired in the usual manner.

I claim:-

5. 1. In an internal combustion engine of the two cycle type, in combination, a working and a charging cylinder, a barrel between same, a piston in said working cylinder having a tubular extension adapted to recipro-
- 10 cate in said barrel, a piston on the free end of said extension adapted to reciprocate in said charging cylinder, a fresh air inlet tube concentrically secured into said extension, a charging cylinder cover having externally
- 15 a casing into which the free end of said tube projects and ports in the secured end of said tube adapted to register with ports in the respective end of said barrel.
2. In an internal combustion engine of the two cycle type, in combination a working and a charging cylinder, a barrel between same, a piston in said working cylinder having a tubular extension adapted to reciprocate in said barrel, a piston on the free end of said
- 25 extension adapted to reciprocate in said charging cylinder, mixture inlet ports in

each end of said barrel and two sets of mixture inlet ports in said extension adapted to register with the said barrel ports and convey mixture through said extension from 30 the charging cylinder into the working cylinder, for the purpose specified.

3. In an internal combustion engine of the two cycle type, in combination, a working and a charging cylinder, a barrel between 35 same, a piston in said working cylinder having a tubular extension adapted to reciprocate in said barrel, a piston on the free end of said extension adapted to reciprocate in said charging cylinder, a main pure air supply 40 pipe and a main gas supply pipe, a piston valve located between said two main supply pipes and each of said charging cylinders for conveying pure air and mixture from the respective ends of said charging cylinders 45 to said main pipe, for the purpose specified.

Signed at Manchester, in the county of Lancaster, this 25th day of June, 1919.

JOHN DAVIDSON.
